Primary Examiner — Ralf Seifert(74) *Attorney, Agent, or Firm* — Douglas B. Farrow(57) **CLAIM**

The ornamental design for diaphragm pump, in four embodiments as shown and described.

DESCRIPTION

FIG. 1 is a front isometric view of a diaphragm pump showing our new design;

FIG. 2 is a front view;

FIG. 3 is a left side view;

FIG. 4 is a rear view;

FIG. 5 is a right side view;

FIG. 6 is a top view; and,

FIG. 7 is a bottom view.

The broken lines are included for the purpose of illustrating portions of the diaphragm pump that form no part of the claimed design.
